CLAIM

The ornamental design for a capillary rheometer for measuring dough viscosity, as shown and described.

DESCRIPTION

FIG. 1 is a top, front, and right side perspective view of a capillary rheometer for measuring dough viscosity showing the new design;

FIG. 2 is a top, front, and left side, perspective view thereof;

FIG. 3 is a front elevation view thereof;

FIG. 4 is a right side elevation view thereof;

FIG. 5 is a left side elevation view thereof; and,

FIG. 6 is a top plan view thereof.

The broken lines shown in the drawings illustrate portions of the capillary rheometer for measuring dough viscosity that from no part of the claimed design.

1 Claim, 6 Drawing Sheets
